UNITED STATES PATENT OFFICE.

WINTHROP K. HOWE, OF ROCHESTER, NEW YORK, ASSIGNOR, BY MESNE ASSIGNMENTS, TO GENERAL RAILWAY SIGNAL COMPANY, OF ROCHESTER, NEW YORK, A CORPORATION OF NEW YORK.

POWER-OPERATED WRINGER.

Application filed October 21, 1922. Serial No. 506,074.

This invention relates to feeding devices for power driven wringers for washing machines.

In feeding clothes between the rolls of a power driven wringer, it is generally found necessary to get the end or a fold of a garment close enough to the rolls to be gripped thereby, and in trying to accomplish this the operator sometimes carelessly or accidentally gets the fingers caught between these running rolls. The danger associated with the feeding of clothes in this manner has been recognized and appreciated for some time, and various expedients have been proposed to lessen this danger. In most cases, however, it has been proposed to remedy this danger by providing devices, such as guards and the like, which are provided in order to make it difficult, if not impossible, for the operator to get his fingers between the running rolls. Such devices, however, are likely to materially hinder the feeding of clothes into wringers, and have been found objectionable for this reason.

The present invention contemplates the provision of means to aid the feeding by conveying the clothes to the rolls from a distance, so that the operator need not get the fingers near the wringer rolls. Further objects of the present invention consist in the provision of duplicate equipment on opposite sides of the rolls, so driven that when the wringer is operated in the opposite directions, the conveying means on the feeding side will operate toward the wringer rolls and the conveying means on the discharge side will aid the moving of clothes away from the wringer into a basket.

Other objects, purposes and characteristic features of the invention will appear as the description thereof progresses.

In describing the invention in detail, reference will be made to the accompanying drawings, in which:

Figure 1 shows a front elevation of a wringer constructed in accordance with the present invention, a portion thereof being a sectional view taken on the line 1-1 in Figs. 2 and 3 respectively;

Fig. 2 is a sectional view taken on the line 2-2 of Fig. 1, looking in the direction of the arrows;

Fig. 3 is an end view of the device, a por-

tion of the end cover being broken away to show the driving mechanism;

Fig. 4 is a partial view similar to that of Fig. 2 of a modified form of the present invention; and

Fig. 5 is a section taken on the line 5-5, Fig. 4, as viewed in the direction of the arrows.

In describing the first form of the present invention, reference should be had to Figs. 1, 2 and 3, in which has been illustrated a well-known type of power driven wringer having the usual side frames F and F¹, rolls T and B, and the usual tensioning screws 1, bearing blocks 2, tensioning springs 3, gear housing 4, etc. This wringer also includes a safety release latch, comprising the hinged cross bar 5 having a hinge 6, permitting this bar to be folded upward to release the tension exerted by the springs 3. This bar 5 has its end extending under the projection 7 of re-enforcing plate 8 fastened to the side frame by screws 9, the tensioning screws 1 passing through the bar 5 some distance from the end thereof and resting on the reinforcing members 10 of the cross member 11.

In order to at times maintain the hinged bar 5 in operative relation, a latching device has been provided comprising a latch member L pivotally supported on a support 12 screw-fastened to one of the portions of the bar 5, and having a hook 13 engaging the locking shoulder of the lock plate 14 fastened to the other portion of the bar 5. This latch member L is urged into the locking position by a compression coil spring 15. If for any reasons it is desired to release the tension exerted by the spring 3 as, for instance, if the operator's fingers or garments get caught by the rolls, it is only necessary to press the handle 16 of the latch member L to release the hook 13, thereby allowing the bar 5 to collapse, so to speak, to remove the tension from the top roll T.

To the side frame F¹ and extending along the inside thereof is a bearing plate 20, having outwardly extending flanges 21 fastened to the side frame F¹ by screws 22. On the outside of the other end frame F is provided a casing 23, having extending flanges 24 fastened to the frame by screws 25. Pivotally supported in bear-

ings formed in this bearing frame 20 and casing 23 which together constitute brackets mounted on the wringer is a plurality of conveying rollers R, each comprising a shaft 27, one end of which is squared as shown at 28 and extends into the casing 23, the working portion of the roller shaft 27 being provided with a roller body, covering or lining 33 of rubber, metal, wood or other suitable material. Each shaft 27 has provided thereon a sprocket wheel 29 fastened thereto by washers 30 and cotter pin 31. These rollers, if desired, may be ridged or corrugated longitudinally so as to afford a better gripping surface for conveying clothes thereover.

The lower wringer roll B extends a suitable distance from the wringer to facilitate the connection of a power driven shaft there-
20 to as shown by the extension 35, and is pro-
vided with a sprocket wheel 36 keyed or rig-
idly fastened thereto in any suitable manner
and held in place by the cotter pin 37. A
25 sprocket chain 38 operatively connects the
several sprocket wheels 29 on each of the
rollers R on opposite sides of the wringer
with the sprocket wheel 36 of the lower
30 wringer roll B. The conveying rollers R
may be of any relative diameter as compared
with the diameter of the wringer rolls T
and B, but the diameter is preferably less
35 than that of the wringer rolls. In order to
give the rollers R the same peripheral ve-
locity as that of the wringer rolls T and
B, the ratio of number of teeth on the
40 sprocket wheels 29 to that of the number
of teeth on the sprocket wheel 36 is the same
as the ratio of the diameter of the con-
veying rollers R to that of the wringer
roll B.

It should be noted that the mechanism
casing 23 is provided with inwardly extend-
ing flanges 40 and 41, these flanges 40 and
45 41 preventing clothes from touching the
shafts 27 to prevent spotting of the clothes
from lubricant, and the like, on shafts 27.
The bearing plate 20 is likewise provided
50 with flanges 42 and 43 for the same pur-
pose. The conveying rollers R are prefer-
ably arranged so that the top surfaces de-
fine an inclined plane extending between the
55 wringer rolls T and B, and are prefer-
ably so closely arranged that they just
clear each other, this specific arrangement,
however, not being essential.

In the specific embodiment of the invention
60 illustrated, the wringer is provided with
the usual form of drain board, comprising a
board 45 having its ends provided with
channel members 46 having an upstanding
portion. These channel members 46 are
65 each provided with a slot, as shown by the
dotted line 47 (see Fig. 2), for slidably
supporting this drain board on pins 48 pass-
ing through the end frames F and F¹. In

order to maintain this drain board in its one extreme and tilted position, the side frame F¹ is provided with hooks 49 fastened by screws 50 and adapted to engage notch 51 or 52 of one of the channel members 46, 70 as the case may be, depending on which way the water is to be drained. The casing 23 is provided with a cover 26.

In practice, the wringer will be operated
in one direction or the other, thereby caus-
ing the rollers on the one side of the wringer
to turn in a direction to move the clothes
toward the wringer, whereas the rollers on
the opposite sides thereof turn to move
clothes away from the wringer. If the opera-
tor desires to feed clothes into the wringer,
all that is necessary is that the clothes be held
in a manner so that the end thereof falls
on the conveying rollers and will, by the
rotation thereof, be carried into the wringer.
It should be noted that, although there may
be a slight tendency for a roller to carry
the clothes with it, between it and the next
roller, this is to a large extent prevented
by the next succeeding roller which rotates
to bring the clothes back out again.

In Figs. 4 and 5 has been illustrated a
modified form of wringer feed mechanism in
which the rollers R¹ are sectionalized, and
are arranged in overlapping relation in order
95 that rollers of a predetermined diameter
may be more closely spaced than in the
previous embodiment of this invention. In
general, the wringer construction, bearing
plate and mechanism casing are the same
100 as in the previous embodiment and there-
fore have been given like reference charac-
ters.

In this embodiment of the invention, the
roller shafts 55 are provided with spaced
105 sleeves 56 of suitable material, similar to
that of the lining of the rollers R. These
spaced sleeves 56 are firmly fastened to the
roller shafts 55 in any suitable manner
at points to place these sleeves of adjacent
110 rollers in staggered relation, as more clearly
shown in Fig. 5 of the drawings. The shafts
55 are preferably spaced to just allow clear-
ance between the sleeves 56 of one roller
and the shaft 55 of another roller, and are
115 spaced such a distance from each other that
the several sleeves will just clear each
other. The length of the sleeves 56 is pref-
erably such that clothes are not apt to pass
therebetween, this spacing depending some-
what upon the material used, and the mate-
rial fed into the wringer. Under certain
working conditions, it may be desirable to
make these sleeves very short, and in order
125 to fulfill these requirements it is proposed
to employ disks of metal, rubber or the like,
which are placed on the shaft and are spaced
by washers slightly thicker than the disks,
the disks and washers being forced against
each other in any desired manner.

Having thus shown and described several specific embodiments of the invention, it should be understood that this has been done for the purpose of description only, and that various changes, additions or modifications may be made without departing from the spirit and scope of the present invention.

What I desire to secure by Letters Patent of the United States, is:—

- 10 1. A wringer comprising, a support frame, brackets fastened to the frame, an upper wringer roll, a lower wringer roll, means for forcing said rolls together, a plurality of conveyor rolls mounted in the brackets on one side of the lower wringer roll and having the plane of their top surfaces approximately tangential to the upper surface of the lower wringer roll, a sprocket within one of the brackets on the shaft of each of the conveyor rolls and the shaft of the lower wringer roll, and a chain in driving engagement with each of said sprockets for causing the conveyor rolls to turn in the same direction as the lower wringer roll.
- 23 2. A wringer comprising, a support frame, brackets fastened to the frame, an upper wringer roll, a lower wringer roll, means for forcing said rolls together, a plurality of conveyor rolls mounted in the brackets on one side of the lower wringer roll and having the plane of their top surfaces approximately tangential to the upper surface of the lower wringer roll, a sprocket within one of the brackets on the shaft of the lower wringer roll, a sprocket within the said one of the brackets on the shaft of each of the conveyor rolls, flanges on the brackets enclosing the ends of the wringer roll and conveyor roll shafts and extending inwardly to the rolls proper, and a chain in driving engagement with each of said sprockets for causing

the conveyor rolls to turn in the same direction as the lower wringer roll.

3. A wringer comprising, a support frame, a bracket on each side of the frame, an upper wringer roll, a lower wringer roll, means for forcing said rolls together, a plurality of conveyor rolls on one side of the lower wringer roll and mounted in the brackets, a sprocket wheel on the shaft of the lower wringer roll, a sprocket wheel on the shaft of each of the conveyor rolls, all of said sprocket wheels being enclosed within one of said brackets, and a chain in driving engagement with each of the sprocket wheels for turning the conveyor rolls in the same direction as the lower wringer roll.

4. A wringer comprising, a support frame, a bracket at each side of the frame, a wringer roll carried by the support frame, conveyor rolls carried by the brackets, sprockets on the wringer roll and the conveyor rolls enclosed within one of the brackets, and a drive chain housed by said one of the brackets, and operatively interconnecting the sprockets.

5. A wringer comprising, a support frame, a bracket at each side of the frame, a wringer roll carried by the frame, conveyor rolls carried by the brackets, sprockets on the wringer roll and the conveyor rolls enclosed within one of the brackets, and a drive chain housed by said one of the brackets and operatively interconnecting the sprockets, each bracket having an inwardly projecting flange enclosing the ends of the wringer roll and conveyor roll shafts and terminating substantially flush with the ends of the wringer and conveyor rolls.

In testimony whereof I hereby affix my signature.

WINTHROP K. HOWE.
